UNITED STATES PATENT OFFICE.

LUDWIG J. W. BIRN, OF CHICAGO, ILLINOIS.

DESIGN FOR A ROOF-TILE.

SPECIFICATION forming part of Design No. 29,904, dated December 27, 1898.

Application filed February 4, 1898. Serial No. 669,154. Term of patent 7 years.

To all whom it may concern:

Be it known that I, LUDWIG J. W. BIRN, a citizen of the United States, residing at Chicago, in the county of Cook and State of Illinois, have invented and produced a new and original Design for a Roofing-Tile, of which the following is a specification, reference being had to the accompanying drawings.

Figure 1 is a plan view of a tile made in accordance with my new design. Fig. 2 is a plan of a rear view thereof. Fig. 3 is a longitudinal sectional view thereof, taken on dotted line 3 3, Fig. 2. Fig. 4 is a transverse sectional view of the same, taken on dotted lines 4 4, Fig. 2.

The tile A is used on the flat surface of a roof and has the contours of its upper end a made square and the top surface thereof dished or depressed, so as to form a semicircular shoulder d. The longitudinal sides of the tile are substantially parallel, and midway the length of the left-hand side the adjacent end of the semicircular shoulder takes a slight jog to the left and then continues straight downward, thus leaving a narrow marginal bead e between the upper depressed surface of the tile and lower half of its left-hand side. At a point a little above the middle of the length of the right-hand longitudinal side the tile is provided with a longitudinal ridge d, the width of which is such and is so disposed that its crest projects slightly beyond the plane of the upper half of the side.

The reverse or under side of the ridge d is grooved at d', as shown.

Extending longitudinally and centrally between the sides of the tile is a nose e, which commences at a point within the semicircular limits of the upper part of the depressed top surface of the tile and gradually increases in height as it approaches the lower end e, which latter terminates at a point located at a distance between the lower end of the longitudinal sides of the tile corresponding to approximately about one-half the length of said sides. The lower edges of the said tile are correspondingly curved from the end of the nose e' to the lower ends of the said longitudinal sides, so as to substantially describe a quarter of a circle, and these lower edges are downwardly flanged. The under side of the tile opposite the nose is provided with a longitudinal groove f, which extends down to and through the under side of the end of the nose, and at points nearer the upper end of the under side of the tile is provided with two downwardly-projecting studs or legs g g, which are arranged in the same transverse plane about as shown.

What I claim as new is—

The design for a roof-tile herein shown and described.

LUDWIG J. W. BIRN.
